ELECTROLUMINESCENT MARK SENSING
George Richard Adams, Elkins Park, and Thomas R. Cleary, Drexel Hill, Pa., assignors to Sperry Rand Corporation, New York, N.Y., a corporation of Delaware
Filed Dec. 31, 1956, Ser. No. 631,770
1 Claim. (Cl. 250—219)

The present invention relates to an improved method and apparatus for mark sensing such as may be employed, for instance, in reading documents, and is more particularly concerned with a system of mark or document sensing employing electroluminescent phosphors, whereby more certain mark sensing may be achieved than has been the case heretofore.

It is well known at the present time that information may be placed upon a document, for instance similar to a punch card, by disposing a plurality of spaced marks comprising fluorescent or phosphorescent material on the document, said marks being spaced in accordance with a preselected code. Marks of this general type are ordinarily sensed by stimulating and/or exciting the phosphorescent materials comprising the marks, for instance by means of a source of ultra-violet radiation, whereby the marks emit light which may be detected by an appropriate photosensitive structure. It has been found that document sensing systems, utilizing substantially conventional phosphorescent or fluorescent materials, may often give an incorrect indication of information on a document of card, by reason of the accidental or inadvertent introduction of extraneous luminescent materials on the document; and these extraneous materials are excited along with the marks and emit light, whereby an incorrect determination of the information on the document can occur.

The present invention serves to obviate this difficulty of known sensing systems, and provides a system which is inherently safe from spurious or noise signals due to the excitation of most extraneous luminescent materials which may be present on or in a document being sensed. As will appear subsequently, this improved document sensing is accomplished primarily through the use of marks comprising electroluminescent phosphors, and more particularly those known to exhibit the phenomenon of intrinsic electroluminescence, i.e. luminescence in response to excitation by an electric field.

It is accordingly an object of the present invention to provide an improved mark sensing arrangement.

Another object of the present invention resides in the provision of an improved method and apparatus for mark sensing utilizing electroluminescent phosphors.

Still another object of the present invention resides in the provision of a mark sensing system which is inherently safe from incorrect information sensing due to the presence of false marks or extraneous luminescent materials on or in the document being sensed.

Another object of the present invention resides in the provision of a document sensing system which is more certain in its operation than systems suggested heretofore.

A further object of the present invention resides in the provision of an improved document having marks of electroluminescent phosphors thereon, as well as in the provision of an improved method and apparatus for reading such documents.

A further object of the present invention resides in practical utilization of the fact that electroluminescent marks can be more conveniently sensed while they are being excited than can ultra-violet excited fluorescent marks.

A further object of the present invention resides in practical utilization of the fact that electroluminescent marks can be read while fully excited whereas phos-

2

phorescent marks read during their after-glow period are not radiating as much energy as they were when under the exciting radiation. The mode of excitation contemplated by the present invention furthermore consumes less power than does excitation of luminescent materials by ultra-violet lamps.

In providing for the foregoing objects and advantages, the present invention contemplates the provision of documents having information stored thereon in a pattern of electroluminescent phosphor marks. As will appear subsequently, the number of naturally occurring or synthetic materials which exhibit electroluminescence is relatively small, whereby there is little likelihood that false or extraneous marks of such electroluminescent phosphors could occur in or upon the document.

The electroluminescent phosphor marks are caused to be read from the document by properly exciting the marks; and in particular, this excitation is accomplished in accordance with the present invention by subjecting the marks to an electric field. Proper excitation of the electroluminescent marks, in accordance with the present invention, requires that the electric field be changing in the marks. This changing field effect may be accomplished, as will appear subsequently, by imposing a varying electric field upon either a stationary or moving document containing the marks; or, in the alternative, by moving the document across the boundary of a substantially constant electric field. Since only a relatively few materials are responsive to an electric field to emit radiant energy, the likelihood of false sensing due to extraneous material in or on the document is materially reduced.

The foregoing objects, advantages, construction and operation of the present invention will become more readily apparent from the following description and accompanying drawing.

In particular, referring to the drawing, it will be seen that in accordance with the present invention, an improved method and apparatus for document sensing may utilize an improved document 10, for example similar to a punch card, having one or more groups of marks 11 disposed thereon in accordance with a preselected pattern or code. The several marks 11 comprise, in accordance with the present invention, electroluminescent phosphors carried on or in the document 10. Typical materials which may be utilized in the provision of marks 11 include zinc sulfide, zinc oxide, zinc selenide, cadmium sulfide, cadmium selenide, and mixtures thereof, activated with copper, manganese, aluminum, silver, or mixtures thereof.

Electroluminescent phosphors, of the types comprising marks 11, may be excited by subjecting those marks to an electric field, and in particular, such marks may be excited to emit light by effecting a changing electric field in the marks. Accordingly, the document 10 is utilized in conjunction with a reading apparatus comprising a pair of spaced, substantially parallel electrodes 12 and 13. Document 10 may be caused to pass between said electrodes 12 and 13 by means of appropriate drive means schematically illustrated as rollers 14 and motor 15. It will be appreciated that various drive means may be employed; and it will further be appreciated from the subsequent description that the marks 11 can be read when the document 10 is either moving or stationary, provided proper attention is given to the manner of exciting those marks.

In accordance with one form of the invention, the electrode 12 can comprise a metal or conductive sheet, while the electrode 13 comprises a transparent sheet, e.g. glass, having a transparent conductive coating 16, e.g. an oxide of tin, on a surface thereof. This particular arrangement senses the marks 11 by reason of the light emitted

from those marks passing through the transparent sheet 13. Due to the opacity of sheet 12 no light can pass in a downward direction. In the alternative, however, it will be appreciated that both of electrodes 12 and 13 can comprise transparent materials having transparent conductive coatings thereon, in which event marks similar to 11 can be disposed on both sides of document 10.

Excitation of the marks 11 is accomplished under the control of a potential source 17, the output of which is coupled respectively to conductive electrode 12 (or to the conductive coating thereon), and to the conductive coating 16 on electrode 13. As a practical matter, electroluminescent phosphors of the types comprising marks 11 are excited only when the electric field appearing between electrodes 12 and 13, due to application of potential from source 17, is changing in marks 11. This changing field may be achieved by having the source 17 produce an A.C. output potential; and the application of the resulting changing electric field to marks 11 will excite the marks and cause them to emit light, regardless of whether document 10 is moving or stationary. In the alternative, however, the potential source 17 may produce a D.C. potential output, thereby to effect a substantially constant electrostatic field between electrodes 12 and 13, in which event mark sensing occurs so long as document 10 and marks 11 thereon are caused to move across the boundary of that constant electric field. In either event, however, the desired electric field is effected in the marks whereby the electroluminescent phosphors comprising marks 11 are caused to emit light.

Light so emitted from marks 11 upon the application of an electric or electrostatic field thereto, is detected by a photosensitive detector 18 comprising, in the example illustrated, a plurality of spaced photocells, and if desired, shield means may be interposed between the several photocells comprising detector 18 to assure that each responds only to light emitted by marks in a given position on document 10. In addition, if desired, an optical system 19 may be interposed between electrode 13 and photosensitive detector 18. This optical system may take the form of a lens, as illustrated, or may be more complex in nature, depending upon the requirements of a particular system. In the alternative, however, optical system 19 may be eliminated, provided the level of light emission from the several marks is sufficiently high, and provided the area over which each mark emits light is sufficiently confined to permit a proper sensing to occur.

In the event that electrode 12 comprises a transparent material, sensing of marks on both sides of the document could, if desired, be accomplished; and in this latter form of the invention, a further photosensitive detector 20 analogous to detector 18 could be disposed on the opposite side of document 10, as illustrated.

It will be appreciated from the foregoing, that excitation of marks 11 is accomplished by subjecting those marks to an electric field which is changing in the marks; and it will further be appreciated that only those marks which comprise electroluminescent phosphors will be caused to emit light upon excitation by the aforementioned field. While the electroluminescent phosphors comprising marks 11 do respond to excitation by ultra-violet, it should be further noted that conventional phosphors ordinarily excited by ultra-violet do not respond to an electric field in the manner described.

Accordingly, it is preferable to provide a light-tight housing 21 about the reading apparatus to assure that ultra-violet, and radiant energy of the same wavelength as the marks emit, is positively excluded from the sensing region. As a practical matter, relatively little ultra-violet radiation will be present within a building structure, but the housing 21 is nevertheless preferably provided in order to assure that the only form of excitation applied to the electroluminescent phosphors placed on document 10

is an electric field, whereby the only light detected is that emitted by the excited electroluminescent phosphor marks 11. This arrangement thus eliminates, for all practical purposes, extraneous emissions due to spurious foreign materials which may be present on or in document 10, whereby document sensing in accordance with the present invention provides a more certain and accurate information output than has been possible heretofore.

While we have thus described a preferred embodiment of the present invention, many variations will be suggested to those skilled in the art, and it must therefore be emphasized that the foregoing description is meant to be illustrative only, and should not be considered limitative of our invention. For instance, while transparent electrodes such as 13 (and/or 12) have been discussed in detail, such structures are not in fact essential. The prime consideration of the present invention, in this particular respect, is that the marks be subjected to an electric field whereby said marks emit light, in combination with means for detecting the light so emitted. Accordingly the electrodes, rather than being of a planar transparent material, could take the form of a grid of wires, for example, in which event light passing through spacings between the wires comprising said grid could be detected by appropriate photosensitive structures. Still other modifications will be apparent to those skilled in the art. All such modifications and variations as are in accord with the principles of the present invention are therefore meant to fall within the scope of the appended claim.

Having thus described our invention, we claim:

In an information sensing system, the combination of a document bearing a coded pattern of spaced electroluminescent phosphor marks, a pair of substantially parallel electrodes, a potential source connected to said electrodes for producing an electric field therebetween, roller means for moving said document into, through and out of said electric field, a plurality of photocells for detecting the light emitted from said encoded phosphor marks, said photocells being arranged to detect corresponding phosphor marks in given positions on said document, an optical system for focusing on said photocells the light emitted from said phosphors, and a light-tight housing enclosing said electrodes whereby phosphors on said document are excited only by said electric field.
